UNITED STATES PATENT OFFICE.

FRANK E. CHURCH, OF SCARSDALE, NEW YORK, ASSIGNOR TO NATIONAL INDIA RUBBER COMPANY, OF BRISTOL, RHODE ISLAND, A CORPORATION OF RHODE ISLAND.

DESIGN FOR A SHOE SOLE.

Application filed November 24, 1925. Serial No. 15,534. Term of patent 14 years.

To all whom it may concern:

Be it known that I, FRANK E. CHURCH, a citizen of the United States, residing at Scarsdale, county of Westchester, and State of New York, have invented a new, original, and ornamental Design for Shoe Soles, of which the following is a specification, reference being had to the accompanying drawing, forming part thereof, wherein—

Figure 1 is a plan view, and

Figure 2 is a transverse sectional view, showing my new design.

I claim:

The ornamental design for a shoe sole as shown.

Signed at New York, in the county of New York and State of New York, this 13th day of November, 1925.

FRANK E. CHURCH.
